UNITED STATES PATENT OFFICE.

NICHOLAS STOFFEL AND JESS HAMILTON, OF WELLSVILLE, OHIO.

NUT-LOCK.

1,181,043.

Specification of Letters Patent. Patented Apr. 25, 1916.

Application filed July 10, 1915. Serial No. 39,176.

To all whom it may concern:

Be it known that we, NICHOLAS STOFFEL and JESS HAMILTON, citizens of the United States, residing at Wellsville, in the county 5 of Columbiana and State of Ohio, have invented new and useful Improvements in Nut-Locks, of which the following is a specification.

The present invention relates to improvements in means for locking a nut upon a bolt, and the object of the invention is to provide a nut with a longitudinal groove which communicates with its bore, to arrange within the groove a removable key and 10 to provide the bolt with a key seat which is adapted to receive the key when the nut is screwed home upon the bolt.

With the above and other objects in view, the improvement resides in the construction, 15 combination and arrangement of parts set forth in the following specification and falling within the scope of the appended claims.

In the drawings: Figure 1 is a longitudinal sectional view taken through a nut and bolt constructed in accordance with and provided with our invention, Fig. 2 is a transverse sectional view approximately on the line 2—2 of Fig. 1, Fig. 3 is a perspective view of the bolt, Fig. 4 is a perspective view of the nut, Fig. 5 is a perspective view of the key, Fig. 6 is a perspective view of the split washer, and Fig. 7 is a transverse sectional view illustrating a nut.

35 In the drawings, the numeral 1 designates a bolt of the ordinary construction, the same, however, having its threaded shank provided with an elongated slot 2 providing what we shall term a key seat.

40 Threaded upon the bolt 1 is a nut 3 which is also of the ordinary construction. The nut 3, however, has a longitudinal groove 4 which communicates with its threaded bore and has its sides formed with oppositely disposed parallel slots 5 communicating with the groove 4.

Arranged within the groove 4 and having its arms disposed within the slots 5 is substantially U-shaped key 6, the arms of the 50 key being provided with transverse notches 7, the said notches serving as means for elevating the key to retain the same within the groove 4 and the slot 5 and out of the key seat 2. When the bolt has been fully 55 screwed upon the nut and abuts with plates 8 through which the said bolt passes, the

key 6 will drop by gravity within the key seat 2 and thus retain the nut and bolt effectively locked.

The width of the vertical arms of the key 60 6 are slightly less than the width of the slots 5 so that pressure must be exerted to force the key within the seat 2. Arranged upon the bolt and upon the outer plate 8 is a split spring washer 10, the said washer 65 having its ends spread and one of the said arms or split ends of the washer is adapted to contact with the inner arm of the key 6 to retain the said key in position in the key seat.

If desired and as illustrated in Fig. 7 the 70 arms 11 of the substantially U-shaped key 6 are wedge-shaped, as are also the opposite walls provided by the slot 5', and by such an arrangement an extra amount of 75 force must be exerted upon the ends of the arms to force the same out of contact with the walls of the slot 5' and into engagement with the key slot.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what we claim is:

1. In a means for locking a nut upon a bolt, a bolt having its shank formed with 90 longitudinally extending depression providing a key seat, a nut threaded upon the bolt and having a longitudinal groove communicating with its bore, the sides of the nut having a slot which communicates with the 95 groove, a key member seated in the groove and having an angular end disposed adjacent the slot in the side of the nut, and a member loosely arranged upon the shank of the bolt and adapted, when the nut is 100 screwed home upon the bolt, to contact with the angular arm of the key to force the same in the slot in the side of the nut.

2. In a means for locking a nut upon a bolt, the combination with a superstructure 105 and a bolt passing through the same, the said bolt having its threaded shank provided with an elongated depression forming a key seat, a nut screwed upon the bolt, said nut having a longitudinal groove which 110 communicates with its bore, the sides of the nut having slots which communicate with

the groove, a key including a body member seated in the groove and having angular arms received in the slots and contacting with the opposite walls thereof, a split spring washer arranged upon the bolt and contacting with the superstructure, the ends of the washer being split in opposite directions, and adapted to engage with one of the arms of the key when the said key is forced upon the nut to within the seat of the bolt.

3. In a means for securing a nut upon a bolt, the combination with a bolt having its threaded shank provided with an elongated depression providing a key seat, a nut threaded upon the bolt, said nut having a longitudinal groove which communicates with its bore and having its sides provided with slots which communicate with the

groove, the opposite walls of the slots being angular, a key, said key including a member arranged within the groove and having angular arms, the opposite edges of which being beveled and being arranged within the slots of the nut, said arms having transverse notches, and the said arms adapted under the pressure of force to be moved in the slots to have their connecting member move upon the nut to within the key seat of the bolt.

In testimony whereof we affix our signatures in presence of two witnesses.

NICHOLAS STOFFEL.
JESS HAMILTON.
